United States Patent Office

Des. 185,881
Patented Aug. 11, 1959

185,881

DECANTER

Brooks D. Fuerst, Sylvania, Ohio, assignor to Owens-Illinois Glass Company, Toledo, Ohio, a corporation of Ohio

Application November 7, 1958, Serial No. 53,299

Term of patent 14 years

(Cl. D58—8)

Fig. 1 is a side elevational view of a decanter showing my new design.

Fig. 2 is a top plan view thereof.

The side not shown is the same as the side shown.

I claim:

The ornamental design for a decanter, substantially as shown and described.
